UNITED STATES PATENT OFFICE.

OSCAR O'HALLORAN, OF NEW YORK, N. Y.

CARPET-BEATER.

No. 852,195.

Specification of Letters Patent.

Patented April 30, 1907.

Application filed July 24, 1906. Serial No. 327,491.

To all whom it may concern.

Be it known that I, OSCAR O'HALLORAN, a citizen of the United States, and a resident of the city of New York, borough of Brooklyn, 5 in the county of Kings and State of New York, have invented a new and Improved Carpet-Beater, of which the following is a full, clear, and exact description.

The purpose of the invention is to provide 10 a portable carpet beater, especially adapted to be operated by hand and which is of very simple, durable and economic construction.

A further purpose of the invention is to so 15 construct the device that in operation beater arms of opposing series will be automatically and intermittently raised and permitted to drop under spring control, thus whipping a carpet in the same manner as practiced by hand.

20 Another purpose of the invention is to provide a means for holding all the beaters out of the way within the body of the device when said device is to be transported or stored away.

25 The invention consists in the novel construction and combination of the several parts, as will be hereinafter fully set forth and pointed out in the claims.

Reference is to be had to the accompanying 30 drawings forming a part of this specification, in which similar characters of reference indicate corresponding parts in all the figures.

Figure 1 is a vertical central section taken practically on the line 1—1 of Fig. 2; Fig. 2 is 35 a front elevation of the improved beater; Fig. 3 is a side elevation thereof; and Fig. 4 is a front elevation of a portion of the cam shaft, a cam thereon and a section through a lift arm in connection with which the cam 40 operates.

The body of the device consists of side pieces 10, a connecting top piece 11 and a lower connecting bar 12, preferably located about centrally between the longitudinal 45 edges of the side pieces, and the said frame may be of any desired length or dimensions.

A shaft 13 is fixed in the side pieces 10, being located at the bottom portion of the body, and said shaft is adapted to carry 50 beaters arranged in two series, a series A and a series A', the beaters of the two series extending from the shaft in opposite directions. Each beater is of the same construction, and 55 consists of a body arm 14 having a straight flat bottom longitudinal edge, and preferably its upper edge is inclined or beveled, so that

the body arm 14 is thinnest at its outer end, and a shank member 15 which extends up from the inner end of the body arm 14 and connects with a ring member 16. The ring 60 members 16 are loosely mounted on the shaft 13, and the beaters of the two series are alternately placed on the said shaft and their ring members are held suitably spaced by washers 17 or their equivalents. 65

A second shaft 18 is secured in the side pieces 10 of the body at a point above the beater shaft 13, and springs 19 are secured to the shaft 18, one for each beater. These springs 19 are connected at their lower ends 70 to straps 20, which straps are secured to the rear or inner peripheral surfaces of the ring members 16 of the beaters, as is shown in Fig. 1, the straps connecting with the beaters A' being at that side of the ring members of 75 the beaters which face in direction of the beaters A, while the straps which connect with the ring members of the beaters A face in direction of the beaters A'. A third shaft 21 is also mounted to turn in the said body 80 above the shaft 18, and the shafts 13, 18 and 21 are in vertical alinement. The shaft 21 is provided at one of its ends with a crank handle 21^a, whereby the said shaft is turned. A series of cams B is secured upon the shaft 85 21. These cams correspond in number to the number of beaters employed, and each cam consists of an elliptical body 22 and a segmental tongue 23 integral with the body. These cams B are spirally arranged on the 90 shaft 21, so that the point of one cam is slightly in advance of the point of the next. Two other shafts 24 and 25 are employed, and these shafts are fixed shafts and extend from one side of the body to the other adjacent to the longitudinal edges of the side pieces of the body; and said shafts 24 and 25 are located one at each side of and above the cam shaft 21. 95

A series of lift arms C and C' are loosely 100 mounted at their outer ends on the shafts 24 and 25, the lifting arms C being mounted on the shaft 24 and the lift arms C' on the shaft 25; and the arms on one shaft extend between the arms from the opposing shaft, so 105 that the arrangement of the said lift arms is alternate. The arms C are adapted to operate in conjunction with the beaters A, and the arms C' operate in conjunction with the beaters A'. 110

A strap 27 or its equivalent is attached to the inner end of each of the lift arms C, and

the said straps at their lower ends are secured one to the outer longitudinal edge of the shank 15 of each of the beaters A, and straps 27^a or their equivalents are secured 5 to the outer ends of the lift arms C and to the outer longitudinal faces of the shank members of the beaters A'. In the construction of each of the lift arms a longitudinal opening 26 is made, one end wall of each 10 opening being more or less beveled. The end wall of the opening in arm C adjacent to the pivoted end of the arm is beveled, while the end wall of the opening in the arm C' adjacent to its free end is beveled.

15 When the cam shaft 21 is revolved the hub portion of a cam will engage with the under face of the pivotal portion of the arm above it, and will lift the said arm more or less, and the upward movement of the arm is continued 20 by the engagement of the convexed edge of the tongue of the cam; and as the lift arm operated on is raised through the medium of its attached strap, the beater with which the said strap is connected is likewise raised, and 25 as the beater is rocked in rising its spring 19 is placed under tension; as the arm reaches the opening 26 in the lift arm upon which it has acted it enters the said opening as is shown in Fig. 4, and the arm is then drawn 30 downward by the spring 19, which also forces the body section of the beater violently in engagement with the carpet upon which the machine is placed.

In the operation of this machine, as the 35 shaft 21 is turned the beaters are alternately raised and lowered at opposite sides of the machine and a constant whipping action on the carpet is obtained, which action serves to free the carpet from dust without injury to 40 its texture. Stay strips 28 are normally placed in engagement with the outer faces of the side pieces 10, being temporarily held thereto by set screws 29, which enter suitable apertures 29^a in said side pieces. When the 45 device is set up, however, the stay pieces are removed from their vertical position shown in Fig. 3, and are placed transversely of the bottom portions of the side pieces of the body at their bottom edges, and the set screws 29 50 are then made to enter openings 30 at the lower portion of the side pieces 10. The strips 28 extend beyond opposite longitudinal edges of the body so as to steady the body while the machine is in action. These strips 55 and likewise the lower edge of the body may be provided with casters if so desired.

When the device is not in use the beaters are folded up within the body as shown in Fig. 3, and bars or pins 31 are passed through 60 openings 32 in the side pieces 10 adjacent to their longitudinal edges, crossing the outer faces of the up-lifted beaters and holding said beaters in their upper position, producing a very compact package for transportation and 65 storage.

Having thus described my invention, I claim as new, and desire to secure by Letters Patent,—

1. In a carpet beater, a frame, opposing series of spring-controlled beaters, a shaft 70 upon which said beaters are mounted, series of lift arms for the beaters and connected therewith, and means for raising and releasing said arms.

2. In a carpet beater, a frame, opposing series of spring-controlled beaters in the frame, a support located in the frame and upon which the beaters of the series are alternately loosely mounted, tension devices 80 for the beaters tending to normally hold them in horizontal position, and means for intermittently raising and releasing the beaters.

3. In a carpet beater, a frame, opposing series of spring-controlled beating arms located within the frame, a shaft upon which 85 the said beating arms are loosely and alternately mounted, a series of lifting arms located above the beater arms, the series being oppositely mounted and alternately arranged, and a series of cams for the said lift 90 arms, said cams being spirally arranged upon their support.

4. In a carpet beater, series of oppositely extending beater arms, a shaft upon which the said beater arms are mounted to turn, series of oppositely extending and alternately arranged lift arms pivoted at their outer ends in the said frame, said lift arms corresponding in number and position to the series of beater arms, flexible connections between 100 the outer ends of the lift arms and the outer faces of the beater arms adjacent to the shaft, springs for the said beater arms, supports for the upper ends of the said springs, the lower ends of said springs being attached 105 to the beater arms at their pivotal sections, a shaft mounted to turn below the lift arms, and a series of cams spirally arranged upon said shaft, a cam being provided for each lift arm.

5. In a carpet beater, the combination with a frame, a fixed shaft in the frame, opposing series of beater arms loosely mounted and alternately arranged upon said fixed shaft, opposing series of lift arms located 115 above the beater arms, each lift arm having a longitudinal opening therein, supports upon which the outer ends of the lift arms are pivoted, flexible connections between the free ends of the lift arms and of the beater arms 120 at their pivotal portions, springs secured to the beater arms, opposite the points of attachment of the said flexible connections, supports for the upper ends of said springs, which springs normally tend to hold the 125 beater arms in horizontal position, a shaft mounted to rotate below the lift arms, and a series of cams corresponding in number to the lift arms and spirally arranged upon said shaft, each cam being provided with a seg- 130

mental tongue section, adapted at its convexed surface for engagement with the under face of a lift arm, and in one position of said cam the tongue being adapted to enter 5 the opening in the lift arm permitting the same to drop.

6. In a carpet beater, a frame, a shaft secured in the frame, a series of beater arms loosely mounted on the shaft, an upper series of lift arms, supports upon which said lift arms are pivoted, flexible connections between the free ends of the lift arms and the pivot arms, springs attached to the beater arms, supports for the upper ends of said 10

springs, said springs serving normally to hold 15 the beater arms in horizontal position, a shaft mounted to revolve beneath the lift arms, and cams carried by said shaft for lifting and releasing engagement with said lift arms. 20

In testimony whereof I have signed my name to this specification in the presence of two subscribing witnesses:
